UNITED STATES PATENT OFFICE

SAMUEL W. HATTON, OF VILLA PARK, NEW YORK

ACOUSTIC DIAPHRAGM

Application filed June 18, 1926. Serial No. 116,899.

This invention relates to improvements in acoustic diaphragms particularly for use in connection with sound reproducing apparatus.

5 The invention has for its primary object to provide a diaphragm structure in which resiliency is materially increased in order to increase the efficiency sound reproduction of the diaphragm.

10 The invention comprehends numerous other objects and improvements in the art which are more particularly pointed out in detail in the following description and claims directed to a preferred form of construction, it being understood however that variations may be made in the structure without departing from 15 the spirit and scope of the invention as herein set forth.

In the drawings forming part of this application:

Figure 1 is an elevational view of one side of the diaphragm,

Figure 2 is a similar view of the opposite side thereof,

25 Figure 3 is an edge elevation of the diaphragm.

Figure 4 is a diametrical sectional view taken on a line 4—4 of Figure 1, showing the diaphragm in a partially completed condition 30 and

Figure 5 is a section similar to Figure 4 showing the completed diaphragm structure in which one face has been ground off to provide a smooth surface.

35 In constructing the diaphragm forming the subject matter of this invention, an annealed sheet of iron or other material found suitable for the purpose is provided in the form of a disk, or if desired may be made in 40 other shape than an annular form, and of a size found most suitable for the use to which it is to be placed. The diaphragm is then placed in an anvil or other support and one surface thereof hammered.

45 The diaphragm is indicated generally at 1 in the drawings and in Figure 4 the hammer marks provided in the diaphragm are illustrated at 2 as forming slight indentations or concavities in one surface of the material.

50 In forming these hammer marks it will be

understood that the molecules of the material forming the diaphragm are substantially contracted or compressed throughout the area of the hammer marks.

55 While the diaphragm may be hammered to produce the indentations shown at 3 in Figure 1, it is understood that any other suitable means known in the art for carrying out the same purpose may be used with equal facility, such as by placing the diaphragm in a die press or the like in which the indentations are formed at a plurality of points in regular order or in irregular order, as found most desirable, the indentation covering the surface of the diaphragm or any portion of its 60 surface.

65 The pressure exerted upon the diaphragm during the hammering or other process forming the indentations on one face thereof changes its shape slightly so that it will be of 70 slightly concavo-convex form throughout the compressed section thereof. This formation also increases the tension and resiliency of the diaphragm and imparts equalities to the material which make it resonant to a wide range 75 of sound wave frequencies.

75 After the diaphragm is provided with the hammer marks at points of variable compression, as above described, the hammered or compressed surface thereof as shown in Figure 4 is ground to remove the projection or irregularities caused by the hammer marks so as to provide a completed diaphragm structure of concavo-convex formation in which 80 both surfaces are smooth, but in which molecular compression of variable or increased density is maintained in the body of the diaphragm.

85 The diaphragm in itself is considerably more resilient than before the hammer treatment and as a result it is resonant to a wide 90 range of sound frequencies within the audible group and will reproduce audible sound in a highly efficient manner and with natural tone reproduction.

95 It is obvious that my invention is susceptible to various changes and modifications in construction without departing from the spirit of the invention or the scope of the appended claims, and I accordingly claim all 100

such forms of the device to which I am entitled.

I claim:

1. An acoustic diaphragm of concavo-convex form having a plurality of regions of the material constructed of variable density for increasing resiliency of the diaphragm.
2. An acoustic diaphragm of concavo-convex form having smooth surfaces and provided with regions of increased density in its body for increasing the resiliency of the diaphragm.

In testimony whereof I affix my signature.
SAMUEL W. HATTON.
